United States Patent Office

Des. 184,946

Patented Apr. 21, 1959

184,946

WHEEL COVER

William F. Lange, Detroit, Mich., assignor to General Motors Corporation, Detroit, Mich., a corporation of Delaware

Application December 1, 1958, Serial No. 53,591

Term of patent 7 years

(Cl. D14—30)

Figure 1 is a front elevational view of a wheel cover showing my new design;

Figure 2 is a side elevational view;

Figure 3 is a sectional view taken along the plane indicated by line 3—3 of Figure 1;

Figure 4 is an enlarged perspective view of a portion of Figure 1; and

Figure 5 is a perspective view.

I claim:

The ornamental design for a wheel cover, substantially as shown.
